UNITED STATES PATENT OFFICE

155,875

DESIGN FOR A DRIP CONTAINER FOR TOILET FLUSH TANKS

Gus Davidson, Chicago, Ill.

Application March 18, 1947, Serial No. 137,696

Term of patent 14 years

(Cl. D4—5)

To all whom it may concern:

Be it known that I, Gus Davidson, a citizen of the United States and a resident of Chicago, in the county of Cook and State of Illinois, have invented a new, original, and ornamental Design for a Drip Container for Toilet Flush Tanks, of which the following is a specification, reference being had to the accompanying drawing, forming a part thereof.

Figure 1 is a perspective view of a drip container for toilet flush tanks, showing my new design.

Figure 2 is an end view of the pan shown in Figure 1.

This drip container is characterized by an inwardly bowed and flaring front wall of the specific curvature shown.

I claim:

The ornamental design for a drip container for toilet flush tanks as shown, and described.

GUS DAVIDSON.
